US0D1106170S

(12) **United States Design Patent** (10) **Patent No.:** **US D1,106,170 S**
(45) **Date of Patent:** **** Dec. 16, 2025**

(54) **SMART WATCH**

(71) Applicant: **Shenzhen Yuanhuan Technology Co., LTD**, Shenzhen (CN)

(72) Inventor: **Xiaoyong Li**, Shenzhen (CN)

(73) Assignee: **Shenzhen Yuanhuan Technology Co., LTD**, Shenzhen (CN)

(**) Term: **15 Years**

(21) Appl. No.: **29/915,107**

(22) Filed: **Oct. 25, 2023**

(51) LOC (15) Cl. **14-02**

(52) U.S. Cl.

(57) **CLAIM**

The ornamental design for a smart watch, as shown and described.

DESCRIPTION

FIG. 1 is a front perspective view of a smart watch, showing my new design in a closed configuration;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front perspective view, showing the smart watch in an expanded configuration; and,

FIG. 10 is a rear perspective view thereof.

The broken lines in the drawings illustrate portions of the smart watch that form no part of the claimed design.

1 Claim, 10 Drawing Sheets
